BUILT-UP PARTITION PILLAR

Application filed November 24, 1928. Serial No. 331,705.

This invention relates to an improved built-up partition pillar, and has for its object an improved organization of parts which is not only capable of economical assemblage and erection, but as well furnishes a space in the structure of the relatively slight T-partitions now so much used for the subdivision of office space, within which is provided space for the entirely concealed presence of a conduit pipe or other communicating element. Not only does it adapt itself to the limitations as to thickness which must be borne in mind as to partition structures of this character, but as well it constitutes a very strong bracing or reinforcing medium for the entire parts, the glass and enclosing frame portions of which are necessarily of relatively light construction, and may be very easily taken down and reassembled without injury to the component parts.

In the drawings:

Figure 1 is a perspective view of a horizontally severed portion of my improved partition pillar.

Figure 2 is a sectional plan view thereof. Figure 3 is a floor-to-ceiling sectional elevational view of this pillar construction, bringing out as well the possibility of its use for enclosure of horizontally extending pipes as well as those which extend vertically.

Figure 4 is a fragmentary front elevational view of a wood and glass partition construction, wherein the built-up pillar features herein disclosed are embodied.

A represents a pipe or conduit, which it is desired to enclose within the physical confines of a partition pillar, horizontal or vertical, which are positioned at suitably reinforced intervals in a glass-and-wood partition structure, such as is frequently employed in dividing a relatively large office or factory space into two or more individual rooms. This pipe or conduit is spacedly surrounded by a rectangular construction formed by plain panel pieces C and D, and marginally tongued pieces E and F, which, when correlated in the manner herein to be described, leaves a rectangular space available for the positioning therewithin of the pipe or conduit A. The lateral or exposed panels E and

F are provided with marginal tongues or beadings B which engage the lateral edges of the panels C and E, while the adjacent marginal portions of their interior faces rest against the undercut or checked edges of the panels E and F inside of the marginal tongues B. The firm and permanent correlation of the parts as thus described may be effected either by gluing of the adjacent surfaces, or, as illustrated in sectional Figure 2, by means of screws H, which pass through the marginal edge portion of the panels C and D, transversely of the planes thereof, and extend into the wood of the panels E and F coincidentally with the planes thereof. Outside of and marginally over the tips of the tongue B on the panels E and F engage the overbent or projecting edge portions J of the spanner or correlating panels G, the intermediate interior faces of which lie flat against the exterior and otherwise exposed panels C and D, which may be structurally united by gluing or by the screws K which pass preferably at a slight angle through the body of each spanner member and into the wood of the adjacent plain panels C and D at points which do not interfere or conflict with the already positioned screws H. In the center portion of each of these spanner panels there may be provided kerfs L, within which are inserted the marginal edges of the glass panes M, or, if desired, of relatively thin panels of wood N, which generally constitute to chair-rail height the lowest sections of the T-partition as a whole.

While primarily adapted for the vertical reinforcement of the partition structure as a whole, such a built-up pillar as is here disclosed may, with equal facility, be used for horizontal purposes as shown at P in Figures 3 and 4, being preferably positioned at about the height of, and functioning very acceptably as a chair-rail contouring of the T-partition at that elevation.

It will thus be seen that this built-up pillar construction not only possesses structural and appearance advantages over an ordinary rectangular box pillar, but that the overengaging marginal edge portions J of the spanner members serve to not only addition-

ally correlate the panel pieces, but as well cooperate with them in lending additional rigidity to the structure as a whole.

Having described my invention, what I claim is:

1. A built-up partition pillar, comprising a pair of plain bounding panels, a pair of marginally tongued panels adapted to cooperate with said plain panels in rectangularly enclosing a hollow central portion, and a spanner piece provided with overengaging marginal edges, adapted to hold the opposingly located tongue portions of the panels thus formed in firm engagement against the ends of the adjacent plain bounding panels.
2. In combination with a plurality of pairs of initially separate panel members, one pair having their edge portions tongued for engagement with the edge portions and the adjacent surface portions of the other pair of panels when arranged about an unoccupied central space, spanner pieces engaging over the tongued opposing edge and marginally over the outer lateral surfaces of the tongued panels, to hold them firmly in their described position against the ends of the other pair of panel members, and screw members structurally correlating the spanner members and the adjacent plain panel portions.
3. In combination with a pair of plain panels and a pair of marginally tongued panels opposingly arranged in cross-sectionally rectangular relation about an unoccupied central space, the ends of the plain panels being overengaged by the tongued marginal portions of the second pair of panels, spanner members provided with inturned edge portions adapted to correlatively engage over the opposing tongued edge portions of the second pair of panels, and removable uniting screws, each of which passes through or into not less than two of the enumerated parts.
4. A built-up partition post, having in combination a plurality of panels which marginally over-engage one another, thereby surrounding an unoccupied central space within which a pipe or conduit may be located, correlating screw members engaging through the meeting marginal portions of the several panels transversely of the plane of one of the panels traversed and coincidentally with the plane of the other adjacent panel, a spanner member positioned in parallel relation with two of the panels and overengaging with its overbent marginal edges the adjacent end portions of the panels whose planes extend transversely thereof, and screw members passing through each spanner member and the adjacent parallel positioned panel.
5. A built up partition post, consisting of a pair of spacedly disposed plain panels, and a pair of spacedly disposed marginally tongued panels arranged in perpendicular relation to the first named pair, the end portions of which latter fit in the shoulders con-

stituted by the tonguing of the second named pair of panels in a way to position the tongued end surfaces of said second pair of panels in the same plane with the outer surfaces of the corresponding panels of the first named set, screw members engaging transversely of the planes of the first named pair of panels and lengthwise of the planes of the second named pair of panels for effecting their structural correlation about an available central space, spanner members arranged in pairs on either side of an interposed glass pane in a manner to concealingly cover the plain panel members first above recited and the overlapping tongued ends of the second named pair of panel members as well as the marginal edges of the exposed outer faces of the latter, thereby additionally holding the latter against displacement, and screw members passing through each unit of said spanner members into the bodies of the respective adjacent plain panel members.

In testimony whereof I sign this specification.

ISAAC H. MORRISON.
